CHANGE MAKER

Filed April 11, 1928

UNITED STATES PATENT OFFICE

THEODORE JOHN HOGLUND, OF GARDNER, MASSACHUSETTS, ASSIGNOR TO GARDNER SCREW CORPORATION, OF GARDNER, MASSACHUSETTS, A CORPORATION OF MASSACHUSETTS

CHANGE MAKER

Application filed April 11, 1928. Serial No. 269,212.

This invention relates to portable coin-holding change makers especially adapted to hold and dispense coins of the lower denominations, although not necessarily limited to such specific use.

The main object of the present invention is the provision of a coin changer that has all its parts permanently secured together, so that the parts can not become loose or 10 separated and the device thus become inoperative or unsatisfactory in operation.

Another object of the invention is the provision of a coin changer which is inexpensive and can be assembled readily without 15 error.

A further object of the invention is generally to improve the construction and operation of coin changers.

Fig. 1 is a front elevation of the device 20 embodying the invention.

Fig. 2 is a plan view of the device partly in section taken along line 2—2 of Fig. 1.

Fig. 3 is a section along line 3—3 of Fig. 1.

Fig. 4 is a bottom view of the device.

Fig. 5 is a perspective sectional view taken along line 5—5 of Fig. 1.

Fig. 6 is a section taken along line 6—6 of Fig. 5.

Fig. 7 is a plan view of the intermediate or coin-tube holding plate.

Fig. 8 is a perspective detail of one of the coin discharging levers.

The coin-changer embodying this invention comprises the bottom plate 10, the intermediate or coin-tube holding plate 12, the cap plate 14, the back plate 16, and the coin-holding tubes 18. Each coin holding tube 18 is formed from a flat sheet of metal reflexed into tubular form with confronting opposed vertical edges and having staggered vertically elongated slots 20 through which the stack of coins within the tube is visible. The tubes are all of different internal diameters which correspond with the diameters

of the coins of different dimensions which the tubes are adapted to hold. The tubes are opened their full diameter throughout. Said tubes are supported by the intermediate plate 12 which plate is drawn out to provide a series of apertures 22 therein and integral upstanding flanges 24 which surround said apertures. The lower ends of the tubes are pressed frictionally into said apertures and into frictional engagement with the upstanding flanges 24. The tubes are provided with circumferential radial outstanding beads 26 at their lower ends which engage the top edges of said flanges and thus limit the extent to which the tubes can be inserted in said apertures. The beads are so arranged that the open bottom ends of the tubes are substantially flush with the bottom of the plate 12. The intermediate plate 12 is generally conformed in configuration with the bottom plate 10 and is supported in spaced relation to and above said bottom plate. To this end, the plate 12 is provided with depressed sections 12a, see Figs. 6 and 7, between the tube-apertures which sections bear upon the top face of the bottom plate and form bosses that support the intermediate plate in spaced relation above the bottom plate. The rear end corners 12b of the intermediate plate are also reflexed downwardly and provide similar bosses that rest upon the bottom plate.

Rivets 28 are passed through the bosses 12a of the top plate and also through the bottom plate whereby to secure the two plates rigidly and permanently in the aforesaid relation.

The cap plate 14 overlies the open ends of all the coin-tubes 18 and is provided in its end face with recesses 30 into which the top ends of the tubes are pressed. The intermediate and cap plates serve to hold the tubes in cylindrical form, with the confronting edges of the plates composing the tubes substantially in contact and the resiliency of the metal plates composing the tubes serves to

- press the sides of the tubes in firm frictional engagement with said cap and intermediate plates. The cap plate 14 above the recesses are provided with slots 32 therein in which 5 coins can be inserted to fall into the interior of the tubes. The widths of the slots 32 are such that a coin larger than the coin of the intended denomination which the tube is adapted to receive can not pass through the 10 slots. The integral depending ears 34 are in-turned into apertures 36 in the front of the tops of the tubes and bear firmly against the upper edges of the slots, thus to lock the cap plate firmly and permanently upon the tops 15 of the tubes. Vertical posts 38 are located at the intermediate and bottom plates and have the upper ends 40 which extend through and are headed over the rear corners of the cap plate. Said posts also have reduced ends 42 20 extending through aligned apertures 44 in the depressed corners 12b of the intermediate plate and bottom plate and are headed over the bottom plate, thus additionally securing the intermediate and bottom plates permanently together and also securing the cap plate rigidly and permanently to the intermediate and bottom plates. The coin-tubes thus 25 are clamped irremovably and fixedly between the caps and plates.
- 30 The back plate 16 is located at the rear edges of the bottom and intermediate plates and upstands thereabove for a substantial distance, and is permanently secured to the bottom plate by tabs 46 thereof which extend through slots in the back plate and are headed over against the back plate. The back plate also is provided with integral forwardly directed extensions 16a at the ends thereof which overlie the ends of the intermediate and bottom plates and are secured to the bottom plate by tabs 46a that extend through 35 said extensions and are headed over thereagainst.
- 40 The upper edge of the back plate above said end extensions 16a is also provided with ears 48 which are reflexed about the posts 38 and thus connect the back plate permanently with said posts.
- 45 The front edge of the bottom plate is provided with notches 50 of generally circular formation which partially underlie the open bottoms of the coin-tubes so that a coin when ejected from a tube can fall through the notch disposed beneath the tube. The bottom plate, however, overlies a sufficient extent 55 of the bottom of the tube to prevent the coins from escaping unintentionally therefrom.
- 50 The space between the bottom and intermediate plates under each coin-tube should not be much greater than the thickness of a single coin which is adapted to be held by the tube, for the dispensing of a single coin at a time. To this end, the bottom plate 10 is 60 provided with upstanding integral bosses 52

which underlie certain of the tubes, as the two end tubes and are elevated above the general surface of the bottom plate to sufficiently provide a space between the bottom plate and the intermediate plate that is not much greater than the thickness of a single coin. 70

The coin ejector mechanisms include pivoted rings 54 which are located under the tubes between the intermediate and bottom plates and have openings 56 therethrough 75 which correspond in diameter to the specific coin to be dispensed. The thickness of each ring is adapted to correspond with the thickness of the particular coin to be dispensed.

Each ring is provided with an ear 58 that is pivoted upon an apertured circular boss 60 which boss is integral with and is drawn down from the material of the intermediate plate 12 to provide a pivotal support for the ring. The boss also serves as a spacer member to separate the intermediate and bottom plate. The bosses 52 are also extended under the pivot bosses 60 to prevent the rings from becoming disengaged therewith. An up-standing boss 53 is also formed under the pivot boss of the middle tube for the same purpose. The ear of the ring is also provided with a circular opening 62 for engagement with an operating lever. 80

The intermediate and bottom plates are 95 provided with registering elongated slots 64 therein which are in register with the circular openings 62 of the rings and are adapted to admit entrance of the operating levers into the openings of the rings and permit the reciprocation of said levers. 100

An operating lever 66 is provided for each ring. Said operating lever is formed of a single sheet of material having downwardly reflexed spaced ears 68 providing pivotal supports for the lever. The lever is also provided with an integral downwardly extended finger 70 which extends through a slot 64 of the intermediate and bottom plates and is received loosely in the circular opening 62 of the ring with which it is associated. 110

All of the levers are pivotally mounted upon a pivot pin 72 which is passed loosely through the openings 74 of the ears 68 of the levers and is fixed in forward extensions 76 which are struck out of the back plate 16. The pin is curved to correspond with the curve of the back plate. Coil springs 78 encircle 115 said pin between the ears 68 of the levers and have their opposite ends bearing respectively against said levers and the back plate in a manner to maintain said levers in elevated position and the rings under their respective tubes. The rings are provided with projections 80 at their rear faces which are adapted to be maintained against the back plates 16 by the springs 78 and thus form stop members to limit the inward movement 120 of the rings. Said projections of each ring are differently shaped so that the rings can 125

130

be identified readily and assembled under the operating tubes with but small chance for error. The lower ends of the fingers 70 are adapted to bear against the rear ends of the 5 slots 64 in the intermediate plate, when the levers are depressed to eject a coin, thus to determine the operated position of said rings and levers.

It is apparent that when said levers are 10 depressed the rings will be moved outwardly as shown at the right end portion of Fig. 2 and when the levers are released, the springs 78 serve to retract the rings into a position under said tubes as shown at the left of Fig. 2.

15 The construction above described is simple and inexpensive, utilizes a minimum of parts and yet the various components of the device are held rigidly and permanently together.

20 I claim:

1. A coin-changer comprising an intermediate plate and a bottom plate, said intermediate plate having apertures, coin-tubes aligned with said apertures, said intermediate and bottom plates being in spaced relation and said intermediate plate having integral depressed circular bosses on its lower face located mainly at the rear of said coin tubes and which occupy the space between 25 said plates and bear against said bottom plate whereby to maintain said plates in spaced relation, said intermediate plate having circular depressions in its upper face at said bosses, and rivets passed through said 30 bosses and said bottom plate which maintain said plates in the aforesaid relation, the heads of said rivets lying in said depressions and being below the upper face of said 35 intermediate plate.

40 2. In a coin-changer, the combination of spaced intermediate and bottom plates, a coin-tube arranged in register with an aperture in said intermediate plate, a coin-ejector ring located between said plates and supported by said bottom plate under said tube 45 and having an ear which has a pivotal connection with one of said plates and an opening beyond said pivotal connection, said plates having elongated slots which overlie 50 said ear and the opening therein and which are located at the side of the tube near the front edges of said plate, and a lever having a projection which is passed through said slots and is loosely received in the opening 55 of said ear.

55 3. In a coin-changer, the combination of spaced intermediate and bottom plates, a coin-tube arranged in register with an aperture in said intermediate plate, a coin-ejector ring located between said plates and supported by said bottom plate under said tube 60 and having an ear which has a pivotal connection with one of said plates and an opening beyond said pivotal connection, said plates having elongated slots which overlie 65

said ear and the opening therein and which are located at the side of the tube near the front edges of said plate, and a lever having a projection which is passed through said slots and is loosely received in the opening 70 of said ear, said projection adapted to engage the end of said slots whereby to limit its movement and also the movement of said ring in one direction.

4. In a coin-changer, the combination of 75 spaced intermediate and bottom plates, a coin-tube arranged in register with an aperture in said intermediate plate, a coin-ejector ring located between said plates and supported by said bottom plate under said tube 80 and having an ear which has a pivotal connection with one of said plates and an opening beyond said pivotal connection, said plates having elongated slots which overlie 85 said ear and the opening therein and which are located at the side of the tube near the front edges of said plate, and a lever having a projection which is passed through said slots and is loosely received in the opening 90 of said ear, said projection adapted to engage the end of one of said slots whereby to limit its movement and also the movement of said ring in one direction, and a spring associated 95 with said lever to return it and said ring to an unoperated position, said ring having an abutment which supports said ring and lever against the action of said spring.

5. A coin-changer comprising vertically 100 spaced intermediate and bottom plates, a coin-tube arranged in register with an aperture in said intermediate plate, a back plate fixed to said bottom plate and overlying the space between said two plates, a pivoted coin-ejector ring located between said plates and supported by said bottom plate under said tube 105 and having a pivotal connection with one of said plates, and a spring-pressed operating lever having a loose connection with said ring, said ring having an extension 110 which is adapted to engage said back plate in an unoperated position of said ring.

6. A coin-changer comprising vertically 115 spaced intermediate and bottom plates, coin-tubes adapted to contain coins of different denominations located above and in register with openings in said intermediate plate, said bottom plate having integral elevated bosses which underlay said coin tubes, and coin-ejector members underlying said intermediate plate and overlying said bosses, said bosses being of different heights and providing spaces of different heights between them and said intermediate plates which correspond with the thicknesses of the coins in said tubes. 120

7. A coin-changer including the combination of a plurality of vertical coin-tubes, a cap-plate bearing against the tops of said tubes and extended rearwardly thereof, an intermediate plate having flanged apertures 125 130

- in which the bottom ends of said tubes are pressed, a bottom plate underlying and spaced below said intermediate plate, coin-ejector mechanism located between said plates, depressible levers for said ejector mechanism located above said intermediate plate and between said tubes, said intermediate plate having integral down-struck bosses under said levers which bear upon said bottom-plate and space said plates apart, rivets passed through said bosses and bottom-plate securing both plates rigidly together, said intermediate plate also having struck-out ears beyond said levers which bear upon said base plate, and rods passed through said ears and bottom plate and riveted rigidly thereto and also passed through said cap-plate and riveted rigidly thereto.
8. A coin-changer having the combination of an intermediate generally rectangular plate, coin-tubes carried thereby and upstanding thereabove at the forward edge of said plate, a generally rectangular cap plate overlying the tops of said tubes and having recesses therein at its forward edge in which the tops of said tubes are located, a generally rectangular bottom plate disposed in spaced relation beneath said intermediate plate, said intermediate plate having rear down-struck corners which bear upon said bottom plate, vertical posts passed through said corners and bottom plate and riveted rigidly thereto and also passed through and riveted rigidly to said cap plate.
9. A coin-changer having the combination of an intermediate generally rectangular plate, coin-tubes carried thereby and upstanding thereabove at the forward edge of said plate, a generally rectangular cap-plate overlying the tops of said tubes and having recesses therein at its forward edge in which the tops of said tubes are located, a generally rectangular bottom plate disposed in spaced relation beneath said intermediate plate, said intermediate plate having struck-out circular depressions in the rear of and between said coin tubes and corresponding projections from its bottom face which bear against said bottom plate and constitute means to hold it in spaced relation with said intermediate plate, said intermediate plate having rear down struck corners which also bear upon said bottom plate, vertical posts passed through said corners and bottom plate and riveted rigidly thereto and also passed through and riveted rigidly to said cap plate.
10. In a coin-changer having spaced intermediate and bottom plates, a coin-tube registering with an aperture in said intermediate plate, a pivoted coin-discharging ring located between said plates under said coin-tube, and an operating lever for said ring having an operative connection therewith, said ring having an ear provided with an opening, and said intermediate plate having

an integral struck-out depending cylindrical projection which extends loosely through said opening in the ear of said ring and which comprises a pivotal support for said ring, said bottom plate underlying said projection and serving to maintain said ring in pivotal engagement with said projection.

In testimony whereof, I have signed my name to this specification.
